UNITED STATES PATENT OFFICE

CLIFFORD BANTA AND FRANK WELDON HIGHTOWER, OF PHILADELPHIA, PENNSYLVANIA, ASSIGNORS TO THE BARRETT COMPANY, OF NEW YORK, N. Y., A CORPORATION OF NEW JERSEY

PROCESS FOR TREATING TAR ACIDS

No Drawing.

Application filed November 24, 1928. Serial No. 321,758.

Our invention pertains to the purification of tar acids and relates more specifically to a process for the reduction of the sulfur content of tar acids.

In the coal tar industry a so-called "sodium carbolate" is one of the products formed. This material, which is usually obtained as an aqueous solution varying in concentration over a considerable range, contains the sodium salts of phenol, cresols, xylenols, and similar aromatic hydroxy compounds. Tar acid is commonly produced by adding sufficient inorganic acid to a sodium carbolate solution to react with the basic radicle and liberate the tar acids which are then removed by decantation from the resultant aqueous solution containing inorganic sodium salts which may also be present in insoluble crystalline form. The tar acids thus liberated and decanted are usually treated with the amount of alkali required to remove excess inorganic acid. The crude tar acid thus produced contains, on the average, about 15% of water and from 0.1 to 0.5% of sulfur and in extreme cases has been known to contain as much as 3.0% of sulfur.

The presence of even the average quantities of sulfur in tar acids is objectionable and, while various attempts have been made in the past to reduce the sulfur content of these materials, no practical process has been available which would remove the major portion of the sulfur content. We have now discovered a process whereby as much as 85 to 95% of the sulfur content of tar acids may be removed. Our process is applicable not only to crude tar acid as usually produced in the coal tar industry but to tar acids produced by other processes and to individual acids such as phenols, cresols, xylenols, and similar substances.

Our process comprises the treatment of tar acids at elevated temperatures with small amounts of aromatic sulfonic acids or the salts of such acids, and the subsequent distillation of the treated tar acids. In practise, we prefer to carry out this treatment by digesting the tar acids in the presence of about 1% of a salt of an aromatic sulfonic acid or in the presence of an equiva-

lent quantity of the free acid. Subsequently we distill the previously digested tar acids under diminished pressure, and as a result of this treatment we are able to remove as much as 85 to 95% of the sulfur originally present.

Suitable aromatic sulfonic acids for this purpose include naphthalene sulfonic acid, benzene sulfonic acid, cresol sulfonic acid, sulfanilic acid and similar acids. In place of the free acids we may employ salts of these acids, and we prefer to use for this purpose the alkali or alkaline earth salts. We prefer to digest the mixture at a temperature of about 105° C. for 18-24 hours but the precise temperature of digestion and time of treatment may be varied in accordance with the tar acid treated and with the original sulfur content. After the digestion we prefer to distill the tar acid under a vacuum of about twenty-seven inches of mercury, though a lesser or greater degree of vacuum may be employed.

In the following tabulation we have indicated specific results obtained with four aromatic sulfonic acids in our process. The crude tar acid treated was the product of the Ironton plant of the Semet-Solvay Company and contained approximately 0.22% of organic sulfur. Although the distillation of this acid under about 27" of vacuum, without a previous treatment with an aromatic sulfonic acid reduced the sulfur content appreciably, the sulfur remaining in the distilled product was material. By digesting the crude tar acid with 1% of a salt of an aromatic sulfonic acid for eighteen hours at about 105° C. prior to the vacuum distillation the following results were obtained:

Material used	Per cent sulfur in treated and distilled acid
Calcium naphthalene sulfonate	.0232
Sodium sulfonilate	.0200
Sodium benzene sulfonate	.0225
Sodium cresol sulfonate	.0199
Naphthalene beta sodium sulfonate	.0232
	1.00

All of these products were of satisfactory odor and of marketable quality.

It should be understood that the specific examples given are merely illustrative and are not limiting. We have found that equivalent quantities of free sulfonic acids have the same effect as the salts but we prefer to use the latter materials on account of their greater convenience. In place of the specific salts mentioned we may employ other salts of an aromatic sulfonic acid, though we prefer to use the alkali or alkaline earth salts. While we prefer to employ about 1% of the salts or equivalent proportions of the free acids, our invention is not limited to those precise proportions. The proportion of 1% has been chosen as most suitable for ordinary plant practice but a lesser or greater quantity may be employed if desired. While we prefer to digest the tar acid in the presence of the sulfur-removing reagent, we may maintain the mixture at a temperature somewhat below the digestion temperature and achieve the same result, though a longer treatment is usually required in such cases.

We are aware of the fact that others have proposed the use of mixtures of sulfonic acids and substantial amounts of aldehydes or sugars for the purpose of removing certain acidic sulfur compounds such as mercaptans and thiocresols from tar acids but we believe that we are the first to discover a process whereby practically all of the sulfur present may be removed from the acids without substantial reduction in yield, and in which the reagent employed is an aromatic sulfonic acid or sulfonate not associated with substantial amounts of aldehydes or sugars.

As previously indicated, the salts of aromatic sulfonic acids or equivalent quantities of the acids themselves may be used interchangeably in our process. In the appended claims the expression "a compound containing an aromatic sulfonic radicle" is a generic one and includes both the free acids and their respective salts.

We claim:

1. A process for the reduction of the sulfur content of tar acid which comprises heating said acid in the presence of a compound containing an aromatic sulfonic radicle and in the absence of substantial amounts of aldehydes or sugars, and distilling the resultant product under diminished pressure.

2. A process for the reduction of the sulfur content of tar acid which comprises heating said acid in the presence of a salt of an aromatic sulfonic acid and in the absence of substantial amounts of aldehydes or sugars, and distilling the resultant product under diminished pressure.

3. A process for the reduction of the sulfur content of tar acid which comprises di-

gesting said acid in the presence of about 1% of a salt of an aromatic sulfonic acid and in the absence of substantial amounts of aldehydes or sugars, and distilling the resultant product under diminished pressure. 79

4. A process for the reduction of the sulfur content of tar acid which comprises digesting said acid for about 18-24 hours in the presence of about 1% of a salt of an aromatic sulfonic acid and in the absence 73 of substantial amounts of aldehydes or sugars, and distilling the resultant product under diminished pressure.

5. A process for the reduction of the sulfur content of tar acid which comprises heating said acid in the presence of naphthalene beta sodium sulfonate and in the absence 89 of substantial amounts of aldehydes or sugars, and distilling the resultant product under diminished pressure.

6. A process for the reduction of the sulfur content of tar acid which comprises digesting said acid for about 18 hours in the presence of about 1% of naphthalene beta sodium sulfonate and in the absence 90 of substantial amounts of aldehydes or sugars, and distilling the resultant product under diminished pressure.

7. A process for the reduction of the sulfur content of tar acid which comprises digesting said acid for about 18-24 hours in the presence of a compound containing an aromatic sulfonic radicle and in the absence 95 of substantial amounts of aldehydes or sugars, and distilling the resultant product under diminished pressure.

8. A process for the reduction of the sulfur content of tar acid which comprises digesting said acid for about 18 hours at about 105° C. in the presence of about 1% of naphthalene beta sodium sulfonate and in the absence 105 of substantial amounts of aldehydes or sugars, and distilling the resultant product under about 27 inches of vacuum.

9. In a process for the reduction of the sulfur content of tar acid the step which comprises heating said acid in the presence of a salt of an aromatic sulfonic acid and in the absence 110 of substantial amounts of aldehydes or sugars.

10. In a process for the reduction of the sulfur content of tar acid the step which comprises digesting said acid for about 18-24 hours in the presence of a compound containing an aromatic sulfonic radicle and in the absence 120 of substantial amounts of aldehydes or sugars.

11. In a process for the reduction of the sulfur content of tar acid the step which comprises digesting said acid in the presence 125 of naphthalene beta sodium sulfonate and in the absence of substantial amounts of aldehydes or sugars.

12. In a process for the reduction of the sulfur content of tar acid the step which 130

comprises digesting said acid for about 18-24 hours in the presence of about 1% of naphthalene beta sodium sulfonate and in the absence of substantial amounts of aldehydes or sugars.

5 13. In a process for the reduction of the sulfur content of tar acids the step which comprises digesting said acid in the presence of a compound containing an aromatic sulfonic radicle and in the absence of substantial amounts of aldehydes or sugars.

10 In testimony whereof we affix our signatures.
